UNITED STATES PATENT OFFICE.

EUGENE O. MURMANN, OF GLENDALE, CALIFORNIA.

CAN-OPENER.

1,329,133.

Specification of Letters Patent. Patented Jan. 27, 1920.

Application filed January 27, 1919. Serial No. 273,399.

To all whom it may concern:

Be it known that I, EUGENE O. MURMANN, a citizen of Russia, residing at Glendale, in the county of Los Angeles and State of California, have invented new and useful Improvements in Can-Openers, of which the following is a specification.

This invention relates to a can opener which cuts downwardly through the top of 10 a can.

Heretofore, can openers which operate with a shearing reciprocating movement have been constructed to cut upwardly through the can top, thereby tearing and 15 leaving a projecting ragged edge. It is the principal object of my invention to provide a can opener which will cut downwardly, thereby forcing the cut edge inwardly. It is a further object of this invention to provide 20 a can opener which will cut close to the edge of the can, and which will operate on cans of any contour.

I accomplish these objects by means of the embodiment of my invention illustrated in 25 the accompanying drawing, in which:

Figure 1 is a perspective view of a cylindrical can with my improved can opener in position to cut the top; Fig. 2 is a view showing the knife side of the opener; Fig. 3 is a view of the opposite side of the 30 opener; Fig. 4 is an enlarged section as seen on the line 4-4 of Fig. 3; and Fig. 5 is a top view of the opener.

Referring to the can opener, it comprises 35 a handle 9, preferably formed of metal, a knife 10, and a fulcrum plate 11. The knife has a point 12 and a cutting edge 13. The blade is warped so that the rear is offset from the handle as indicated in Fig. 5 the 40 point 12 is also offset.

The fulcrum plate 11 is secured to the handle parallel to the knife blade and has its forward end offset similar to the knife blade edge. It will be noted from an inspection of Figs. 3 and 4 that the end of the 45 fulcrum member overhangs the point of the knife blade. A hole in the fulcrum plate is threaded and disposed therein is a fulcrum pin 15.

The opener is started by placing the point 50 of the knife edge upon the top of the can with the end of the fulcrum plate resting against the outside lip. The opener is then forced downwardly, the point cutting into 55 the can as shown in Fig. 1. This causes the forward end of the fulcrum plate to slip

over the edge of the can with the fulcrum pin 15 disposed below the lip of the can. The pin is then screwed into position so that its end is underneath the lip, and it will 60 serve as a fulcrum against upward pressure. The handle is now pressed down toward the can as indicated in dotted lines in Fig. 2. The downward movement of the handle causes the knife to cut through the top of 65 the can, and at the same time it flattens the ragged edge against the can. The handle is lifted to the position shown in full lines in Fig. 2, and the opener is pulled toward the operator until the cutting edge comes in 70 contact with the end of the slit in the top of the can. The operation is repeated and in this manner the top is opened.

It is obvious that the fulcrum pin should not be screwed tight against the can so as to 75 prevent sliding the opener around the can. After the top has been cut the pin 15 is retracted so as to permit the withdrawal of the opener from the can. The offsetting of the end of the fulcrum member permits the 80 latter to be disposed under the lip of the can when the can opener is in cutting position and prevent wobbling of the opener. The offset indicated by 14 in Fig. 5 provides for cutting the rounded corners on cans of gen- 85 eral rectangular shape.

What I claim is:

1. A can opener comprising a fulcrum member provided at its forward end with a fulcrum for disposal under the lip of a 90 can, and a blade having its penetrating tip by the side of and extending over said fulcrum whereby to lock said opener to said lip.

2. A can opener for downward cutting movement having a knife blade and a movable fulcrum member by the side thereof to engage under the lip of a can, said fulcrum member having its fulcrum point located so as to be covered by the penetrating tip of the knife blade. 95

3. A can opener comprising a fulcrum member provided with an angular extension, said extension being provided at its forward end with a fulcrum, and a blade extending through the angle between said 100 handle and extension with its penetrating tip covering said fulcrum.

In witness that I claim the foregoing I have hereunto subscribed my name this 20th day of January, 1919.

EUGENE O. MURMANN.
